UNITED STATES PATENT OFFICE

HUBERT A. MYERS, OF TOLEDO, OHIO, ASSIGNOR TO THE MYERS REGULATOR COMPANY, OF TOLEDO, OHIO, A CORPORATION OF OHIO

WINDOW REGULATOR

Application filed January 10, 1927. Serial No. 160,080.

My invention has for its object to provide a simple and efficient automobile window regulator construction that may be made at low cost of construction. The invention pertains to that type of window regulators having a rack to which is connected an arm, the rack being operated by a pinion and the arm operating to raise and lower the window. The invention particularly provides the means for 10 securing the rack and arm in their pivotal relation to a supporting means.

The invention may be contained in structures that differ in their details and, to illustrate a practical application of the invention, 15 I have selected a structure embodying the invention as an example of such structures and shall describe it hereinafter. The structure selected, for purposes of illustration, is shown in the accompanying drawing.

20 Fig. 1 of the drawing illustrates a side view of a portion of the window regulator, selected as an example, to which my invention particularly relates. Fig. 2 is a view of a section taken on the plane of the line looking in the direction of the arrows marked 2-2 in Fig. 1. Fig. 3 is a view of a section taken on the plane of the same line looking in the direction indicated by the arrows marked 3-3 in Fig. 1. Fig. 4 illustrates a perspective view 25 of an oscillatable pivot pin for pivotally supporting the rack. Fig. 5 illustrates a perspective view of the pivot pin shown in Fig. 4 and the manner in which it is secured to one of the parts of the structure whereby one of 30 the parts is pivotally supported relative to the other of the parts.

As is well known in the type of regulators, one of which has been selected as an example of such constructions, a supporting element 40 for the window regulator is commonly secured to what is termed as the lock board, and in such a position that an oscillatable element having a projecting arm that may be connected to the window, usually at the lower edge of the window, and a sector that may be 45 operated by a pinion that is connected to a crank located in a convenient position on the inside of the automobile, whereby the crank may be readily rotated to produce the desired 50 oscillatory movements in the rack and arm to

raise and lower the window to the desired extent. In the form of construction shown, the supporting plate 1 is secured to the lock board by suitable screws or bolts that pass through the openings 2, and if desired to a part of the 55 automobile by a bolt or screw that extends through the opening 3. The oscillatable element 8 of the window regulator is provided with a rack 4 to which is connected the arm 5, the arm 5 having any of the well known 60 means at its outer end for transmitting or transforming its movements into the desired rectilinear movements of the window. If desired the arm 5 may be formed integral with the rack 4 or it may be secured thereto 65 by suitable rivets 6. Also, if desired, the rack 4 may be segmental in form or it may be made arcuate. In the form of construction shown, the rack 4 is arcuate in form and its ends are 70 connected to an end portion of the arm 5 by means of the rivets 6. The rack 4 and the arm 5 are pivotally supported by means of the pivot member 7 that may be formed from a 75 solid bar or from sheet metal. Preferably, the pivot member 7 is formed of sheet metal and has a diameter sufficient to form a good bearing surface for withstanding the strains to 80 which it is subjected to in the operation of the window regulator. The pivot member 7 is preferably connected to the oscillatable element 8 and rotates in the supporting element. The pivot member 7 is connected by inserting 85 in an opening 12 formed in the oscillatable element and is secured from rotation by means of radially projecting flanges or lugs 10 that are located in radial recesses 11 formed in the window regulator. The pivot member 7 has a flaring flange 9 and the lugs 10 extend diagonally from the body of the pivot member 7 to the flange 9. The cylindrical pivot member 7 fits tightly the said opening 12 and as 90 the pivot member 7 is driven home the lugs or flanges 10 enter the recesses 11 which securely locks the pivot member 7 to the oscillatable element 8.

The plate 1 is also provided with an opening for receiving the pivot member 7. The opening in the plate or bracket 1 is formed by depressing the metal so as to form a cylindrical flange 13 about the opening. The 100

flange 13 extends outward with respect to the interior of the automobile and forms a broad bearing for the pivot member 7. The pivot member 7 is positioned in the flange so that the oscillatable element will bear against the plate and thus form a lateral bearing as between the oscillatable element and the plate or bracket 1. If desired, the plate may be stamped to form a raised portion 14 which constitutes the lateral bearing for the oscillatable element of the window regulator. The side or top of the raised portion being of a sufficient width to cover a substantial portion of the oscillatable element, it forms thereby broad bearing areas as between the oscillatable element and the plate or bracket 1.

In the form of construction shown, the counterbalancing spring of the window regulator, that is commonly used for counterbalancing, at least, the major portion of the weight of the window, so that in the operation of the window regulator substantially the same power or force is used in raising the window that is required to lower the window and thus provides a uniformity of action in raising or lowering the window, is connected to the oscillatable element. The counterbalancing spring, in the form of construction shown, is a convolute spring and may be connected at either end, to the oscillatable element, the other end of the spring being anchored to a part of the construction, such as to the plate or bracket 1. Preferably, the inner end of the convolute spring is secured 35 to the pivot member 7 and the outer end is secured to the plate or bracket. The pivot member 7 is provided with a recess 16. The recess 16 may be made L-shape or bayonet shape. Preferably, in order to provide for 40 right and left rotation, or desired location of the operating crank with reference to other parts of the automobile, the recess 16 is formed T-shape. The ends of the convolute spring 15 are hooked and the inner end 18 is located in the recess 16, the depth of the 45 recess being such as to provide for the width of the spring and also to provide for the engaging lugs 19 that extend towards each other. The distance between the juxtaposed 50 surface of the lugs is sufficient to permit the spring to pass between the lugs 19. The distance between the lugs is, therefore, somewhat greater than the thickness of the spring. When the spring has been inserted in position about the pivot member 7, it is drawn 55 so as to be subjected to a sufficient tension as to counterbalance at least the major portion of the weight of the window and the outer end of the spring is anchored to the plate or bracket 1. The hooked end 20 may be hooked over one or the other of the laterally 60 extending lugs or ears 21 according to whether the window is raised by right or by left hand rotation. The initial turn or deformation of 65 the spring from normal, in order to subject

it to the desired counterbalancing tension, locks the spring in position and prevents its displacement while at the same time it operates to counterbalance the weight of the window by transmitting its yielding retentive force through the arm that is connected to the window.

The oscillatable element is retained in its oscillatable relation, not only by the pivot member 7, but also by the supporting plate or bracket 1. The plate or bracket 1 is provided with a recess 23 in which the pinion that operates on the rack 4 may be located, and the plate or bracket 1 is provided with the slots 24 that are formed in the walls of the recess and so that it may be engaged by the pinions that may be located in the recess 23. The rack 4 is formed arcuate and, consequently, as it is moved, it will pass through the slots 24 and thus be held in proper pivotal alignment for the desired oscillatory movements.

I claim:

1. In a window regulator, an oscillatable element and a supporting element, a pivot member connected to one of the said elements and extending through the other of the said elements for supporting the oscillatable element for pivotal movements, the pivot member having radial extending lugs, the element to which it is connected having an opening and recesses extending radially from the said opening for receiving the pivot member and the lugs.

2. In a window regulator, an oscillatable element and a supporting element, a pivot member connected to the oscillatable element and extending through the supporting element, a convolute spring having one end connected to the pivot member and the other end connected to the supporting element and located on the side of the supporting element opposite to that on which the oscillatable element is located, the oscillatable member having an arcuate strip, the supporting element having slots for receiving the said strip and through which the strip moves.

3. In a window regulator, an arm for raising and lowering the window, a supporting member, a pivot member connected to the arm and extending through the supporting member, a convolute spring having one end connected to the pivot member and the other end connected to the supporting member for securing the pivot member in its pivotal relation to the supporting member, an arcuate strip having teeth formed along one edge thereof and secured at its ends to the arm.

4. In a window regulator, an oscillatable element and a supporting element, a pivot member connected to the oscillatable element and extending through the supporting element, a convolute spring having one end connected to the pivot member and the other end connected to the supporting member located

on the side of the side of the supporting member opposite to that on which the oscillatable element is located and for securing the arm in contact with its lateral bearing surface.

5. In a window regulator, an oscillatable element and a supporting element, a pivot member, one end of the pivot member connected to the oscillatable element and extending through the supporting element for pivotally supporting the oscillatable element, a convolute spring, the other end of the pivot member having a slot for receiving one end of the spring by movement of the end of the spring through the slot in the direction of the axis of the pivot member, the spring connected to the supporting element and a lug extending over the slot for maintaining the end of the spring in the slot until it is disconnected from the supporting element.
10. In a window regulator, an oscillatable element and a supporting element, a pivot member, one end of the pivot member connected to the oscillatable element and extending through the supporting element for pivotally supporting the oscillatable element, a convolute spring, the other end of the pivot member having a slot for receiving one end of the spring by movement of the end of the spring through the slot in the direction of the axis of the pivot member, the spring connected to the supporting element and a lug extending over the slot for maintaining the end of the spring in the slot until it is disconnected from the supporting element.
15. In a window regulator, an oscillatable element and a supporting element, a pivot member, one end of the pivot member connected to the oscillatable element and extending through the supporting element for pivotally supporting the oscillatable element, a convolute spring, the other end of the pivot member having a slot for receiving one end of the spring by movement of the end of the spring through the slot in the direction of the axis of the pivot member, the spring connected to the supporting element and lugs extending towards each other and over the slot for maintaining the end of the spring in the slot until it is disconnected from the supporting element and enabling right or left hand connection of the spring for counterbalancing the oscillatable element.

20. In a window regulator, a supporting element, an oscillatable element in contact with the supporting element, a tubular pivot member having a flaring flange and radially extending lugs located at one of its ends and connected to the oscillatable element and extending through the supporting element for supporting the oscillatable element, the oscillatable element having an opening and recesses extending radially from the said opening for receiving the said pivot member and the said lugs, the pivot member having a slot at the other end, a convolute spring located on the side of the supporting element opposite to that on which the oscillatable element is located, and in contact with the supporting element for securing the oscillatable element in contact with the supporting element.

25. In a window regulator, an oscillatable element and a supporting element, a pivot member secured to the oscillatable element and extending through the supporting element and rotatably supported by the supporting element, a convolute spring having one end connected to the supporting element and the other end removably secured to the pivot member and located on the side of the supporting element opposite to that on which

the oscillatable element is located and for securing the pivot member as against axial movement of the pivot member and for securing the convolute spring and the oscillatable element in close proximity to the opposite sides of the supporting element.

In witness whereof I have hereunto signed my name to this specification:
